UNITED STATES PATENT OFFICE.

JOHN D. ELLISON, OF UNION CITY, TENNESSEE.

GARMENT-FASTENER.

1,365,670.

Specification of Letters Patent. Patented Jan. 18, 1921.

Application filed May 4, 1917. Serial No. 166,393.

To all whom it may concern:

Be it known that I, JOHN D. ELLISON, a citizen of the United States, residing at Union City, Tennessee, in the county of 5 Obion and State of Tennessee, have invented certain new and useful Improvements in Garment-Fasteners; and I do hereby declare the following to be a full, clear, and exact description of the invention, 10 such as will enable other skilled in the art to which it appertains to make and use the same.

This invention is a garment fastener designed more particularly for use in connection with the securing of portions of waterproof coats, leggings and the like, although adapted for other use.

A purpose of the invention is to provide a fastener which saves the expense of forming buttonholes; which may be easily operated; which is simple in construction and durable; which can be readily manufactured at a saving of expense in the manufacture, and which saves labor in its application to fabrics.

The fastener comprises a hook member and an eye member, each formed from a single piece of metal, or other suitable material, the eye member being provided with 30 a retaining loop, while the hook member is provided with a hook bent from the base to engage the loop, and with a tongue to retain the hook in engagement with the loop, the tongue being so formed that it will permit of the easy insertion of the loop section between the tongue and hook, and its ready removal from engagement with the hook member, the tongue serving also to prevent the separation of the hook and eye members 35 except when the hook is guided between the tongue and loop.

Other objects and advantages of the invention will become apparent from the following detailed description thereof, taken 45 in connection with the accompanying drawings, in which a preferred embodiment of the invention is disclosed.

In the drawings:—

Figure 1 is a plan view disclosing the 50 complementary members in their co-operative relation.

Fig. 2 is a plan view of the hook member before the tongue and hook portions are formed into their final positions.

Fig. 3 is a plan view of the hook member

with the hook and tongue formed into position.

Fig. 4 is transverse sectional view through the hook member of Fig. 3 disclosing the position of the tongue and the hook. 60

Fig. 5 is a plan view of the eye member.

Fig. 6 is a sectional view through the eye member on the line 6—6.

The garment fastener is shown comprising two members, a hook member A and an eye member B. Each of the members is formed from a single piece of material, such as metal, to provide a base 1 which is shown substantially oval in form. Near the central portion of the base of each member, 70 there may be provided a protuberance 2 which may serve as means to press the thumb or finger against when locking or unlocking the fastener. Near the outer ends of the oval base plate, there may be provided suitable means for securing the base plate to the garment or fabric to which it is attached. In the drawings, the securing means are shown as brads passing through the apertures 3 of the plate 1. These brads are preferably positioned at or about the center of each end of the oval base and substantially equi-distant from, yet adjacent to, the tongue 4 of the hook plate member A. 80

The tongue 4 is cut or formed from the 85 piece of material in such a manner that the base of the tongue is integral with the oval base member 1. The tongue portion is then bent upwardly from the base 1 at an angle of substantially forty-five degrees for about 90 three-fourths of the length of the tongue, and thereafter the tongue is curved or bent slightly downward as at 5 to deflect the end of the tongue for the purpose of permitting the eye member to be more easily fastened 95 and unfastened.

The hook portion 6 of the hook member may be semi-oval in form, as indicated in Fig. 2, and is preferably so bent from the oval base 1 that the free end of the hook, 100 positioned over the end 5 of the tongue and preferably to a point slightly in the rear of the forward bend of the tongue where the tongue is deflected downwardly as at 5. The point 7 of the hook 6 is deflected slightly upwardly to serve as a guide to direct the bar 8 of the eye member between the point 7 of the hook and the end 5 of the tongue. The tongue and hook are so formed on the hook member that they provide a space indicated 110

at 9 between them and the body of the oval base 1, into which may be positioned the bar 8 of the eye member, for comparatively free movement of the bar in such space.

5 The eye member B is provided with an oval base 1, the knob or protuberance 2 and the fastening means 3 are substantially the same as the hook member. The member B however, is provided with an extension 10 which may be substantially rectangular in form, as indicated at 10, and this extension may have a cut-out portion 11 to form an eye, leaving the rest of material adjacent thereto in the form of a loop to be engaged 15 by the hook or member A. The bar 8 forms one side of the loop, and serves as the co-operating retaining means for the hook 6. The extension 10 of the eye member B is deflected slightly downwardly at 12 from 20 the plane of the oval base 1, and at the edge of the base, the deflected portion being preferably positioned at the edge of the material or fabric to which the fastening member B is applied, in order to protect the 25 cloth at that portion. The extension is thence bent again through the side members 13 of the loop to bring the bar 8 of the extension on a plane substantially parallel with the plane of the oval base. In this 30 manner, the eye member B may have its bar 8 so positioned in the space 9 that the

bar is not liable to be moved upon the tongue 5 and hook 6 unless manually directed to such position.

It is obvious that various changes in the 35 form and proportion of parts may be made from those herein described and illustrated, and the right is reserved to make such changes to adapt the invention to various uses, as fairly fall within the scope of the 40 appended claim.

Having thus described the invention, what is claimed as new is:—

A garment fastener comprising complementary hook and eye members provided with 45 bases, having a protuberance substantially centrally of the base and with fabric securing means near the ends of the base, the eye member having a loop bent out of the plane of its base and terminating in a hook 50 engaging section which is on a plane substantially parallel to the base, the hook member having a tongue which co-operates with a hook of the base to prevent the disengagement of the hook engaging section of the 55 loop member from the hook.

In testimony whereof I affix my signature.

JOHN D. ELLISON.
